NEAL J. BURGETT, OF DETROIT, MICHIGAN, ASSIGNOR TO JOSEPH W. HOEHL, OF DETROIT, MICHIGAN

ENAMEL METALLIC TILE

Application filed March 31, 1930. Serial No. 440,595.

The invention relates to tiles such as are used for facing walls in both interior and exterior finish and it is the object of the invention to obtain a construction formed from enameled sheet metal having many advantages over the clay product. To this end the invention consists in the construction as hereinafter set forth.

In the drawing:

10 Figure 1 is a perspective view of my improved tile;

Figure 2 is a cross section showing the tile as laid in a wall;

15 Figure 3 is an enlarged cross section through a portion of a tile and the joint between the same and adjacent tile;

Figure 4 is an enlarged perspective view of the corner construction, and

20 Figure 5 is a plan view of a portion of the blank from which the tile is formed.

My improved construction is formed from a sheet metal blank A which is pressed and fashioned to form inwardly extending flanges B on its several sides and which for a portion 25 of their depth are continuous and integral around the corners as indicated at C. The blank is, however, gored at the corners as shown at D so that the inner portions of the flanges B are separate from each other and 30 are bent at an oblique angle converging towards the center of the tile as shown at E. The front portion is bowed slightly outward as shown in Figure 2 for the purpose herein-after set forth.

35 The sheet metal member formed as just described is then coated with a vitreous enamel on both its external and internal surfaces. The external surface F is smooth and glazed to produce the desired appearance 40 but the internal surface G is rough, thereby forming a better adhesion to the cement or plaster fill. During this enamelling process it is necessary to heat the metal to a temperature where there would be a tendency 45 for it to sag. Such a result is, however,

effectually prevented, first by the outward bowing of the front face and second, due to the fact that a portion of the flange B is continuous and integral around the entire perimeter, thereby resisting any outward 50 thrust due to the sagging of the bowed portion. As a consequence, the finished tile are all of the slightly convexed form which produces a pleasing appearance in the wall.

Another important feature of my improvement is the means which I employ for preventing any cracking of the enamel at the corners of the tile. Such a cracking would occur if the flanges B were separate from each other or in other words, if the gore D 55 were to extend completely to the bend between the flange and the front face. With my construction, however, the fact that the depending flange B is integral around the corners and that the enamel extends continuously over the front face and down the integral side flanges, effectually prevents the forming of any cracks at the corners.

To complete the tile, a cement or plaster core is filled in between the flanges B, being 60 retained by the obliquely converging portions E of said flanges. This core may be made either prior or during the setting of the tile in the wall, preferably the latter. Thus the operator may place the plastic filling 65 in the space between the flanges of the tile and then place the structure against the wall. The plastic filling will thus knit to the wall surface and retain the tile in position. The joint H between adjacent tiles is 70 also filled with a cement and by reason of the oblique portions E, the body of cement between tiles is enlarged at its inner end, which adds to its strength. The tiles may be laid 75 against any surface which is suitable for receiving plaster or cement.

What I claim as my invention is:

80 A tile comprising a sheet metal blank gored at the corners and pressed to form a front face and side flanges, said side flanges 85

being of a depth greater than the depth of the gores to form a portion continuous around the corners, presenting an unbroken surface across the top, part way down the side flanges and around the corners for receiving the enamel finish, the gored portions of said blank being bent obliquely to converge towards the center of the tile to form inclined triangular-shaped openings at the corners, and said sheet metal structure having a vitreous enamel surface outside and inside.

In testimony whereof I affix my signature.
NEAL J. BURGETT.
